UNITED STATES PATENT OFFICE.

WILLIAM HOPPIE, OF SALT LAKE CITY, UTAH, ASSIGNOR TO HOPPIE ELECTRICAL APPLIANCE COMPANY, OF SALT LAKE CITY, UTAH, A CORPORATION OF UTAH.

ELECTRICAL BATTERY.

1,140,826.

Specification of Letters Patent. Patented May 25, 1915.

Application filed June 24, 1914. Serial No. 847,070.

To all whom it may concern:

Be it known that I, WILLIAM HOPPIE, a citizen of the United States, residing at Salt Lake City, in the county of Salt Lake 5 and State of Utah, have invented certain new and useful Improvements in Electrical Batteries, of which the following is a specification, reference being had to the accompanying drawings.

16 This invention relates to certain improvements in electrical batteries and has relation more particularly to a device of this general character known as a dry battery; and an object of the invention is to provide 15 a device of this general character having novel and improved means whereby the life thereof may be materially lengthened and wherein the possibility of evaporation or crystallization of the interior contents of the 20 battery or outside moisture penetrating therein is eliminated.

Furthermore, it is an object of the invention to provide a novel and improved device 25 of this general character wherein mercury and aluminum salts are decomposed by chemical affinity and the metallic atoms electrolytically deposited on the zinc, protecting and prolonging the life of the zinc, making it a more active element and generating a 30 higher electromotive force.

The invention consists in the details of construction and in the combination and arrangement of the several parts of my improved device whereby certain important 35 advantages are attained and the device is rendered simpler, less expensive and otherwise more convenient and advantageous for use, all as will be hereinafter more fully set forth.

40 The novel features of the invention will be carefully defined in the appended claims.

In order that my invention may be the better understood, I will now proceed to describe the same with reference to the accompanying 45 drawings, wherein—

Figure 1 is a sectional view taken through a battery constructed in accordance with an embodiment of my invention; and Fig. 2 is a view similar to Fig. 1, but illustrating a 50 battery constructed in accordance with a further embodiment of my invention.

As disclosed in the accompanying drawings, 1 denotes a container formed from a compressed pulp, such as card-board, and 55 comprising a plurality of laminations be-

tween which is positioned a wrapping 2^b of wire whereby the requisite mechanical strength may be imparted thereto. I also find it of advantage to include in the pulp, from which the container is produced, a 60 suitable cementing compound, such as glue, shellac or the like.

The container is suitably treated to render the same impervious to chemical action and moisture. For this purpose, I prefer to 65 employ a mixture comprising resin, two parts; and eight parts of a substance impervious to chemical action and moisture, such as paraffin wax, asphaltum or the like. This mixture is heated to 225° F. and the 70 container 1 is kept submerged therein until it has become thoroughly impregnated with the mixture, the treatment being continued as long as any of the resinous solution will be absorbed. After the container becomes 75 dry it is coated with shellac or some other hard varnish which coating serves to resist external heat.

2 denotes a thin layer of zinc foil positioned within the container and contacting 80 with the inner surface thereof and adapted to be suitably engaged with a binding post 3.

4 denotes a layer of absorptive material, such as blotting paper or cloth, which engages the inner surface of the layer 2 of 85 zinc foil. After the layers 2 and 4 have been properly inserted within the container 1, the following mixture is placed within the container: glycerin, 1 oz.; gelatin, 8 oz.; sal ammoniac, 8 oz.; aluminum chlorid, 2 oz.; 90 zinc chlorid, 8 oz. This solution results in a thick paste which is left within the container until the absorptive layer 4 is thoroughly saturated with the compound, after 95 which the remainder of the compound is poured out of the container and preserved for future use.

5 denotes the carbon pole inserted within the container at substantially the axial center thereof and projecting a predetermined 100 distance therefrom and having its projected extremity provided with the binding post 6.

7 indicates the filler tightly packed within the container and surrounding the pole 5. In the present embodiment of my invention, the filler 7 comprises 3 oz. of powdered manganese dioxid thoroughly mixed with 9 oz. 105 of powdered carbon. This mixture is then moistened with the following separately prepared solution: zinc chlorid dissolved in 110

water until it tests 32° Baumé scale. Sal ammoniac is then added until the solution is thoroughly saturated therewith. To this solution is then added a soluble mercuric salts, such as mercury bichlorid in ratio of about one-half grain to each cell. In assembling the device care must be exercised that the pillar 7 does not contact with the zinc layer or plate 2.

10 In view of the foregoing, it will be readily perceived that the life of the battery is greatly prolonged, as the aluminum salts are a part of a positive plate and held in the form of a paste to the surface of the 15 zinc layer 2. The mercury salts are mixed with the negative plate or carbon. In action the mercury unites with the aluminum salts and by the great chemical affinity mercury has for zinc, the mercurial atoms combine with the zinc while the external circuit is open. When the external circuit is closed, the metallic atoms tend to travel to the carbon and in this movement the aluminum combines with the mercury salts and 20 returns with the mercurial salts to the zinc layer when the circuit is open. This coating on the zinc layer or positive plate protects it from local action while the circuit is open. I also find that the use of aluminum chlorid 25 prevents the zinc from becoming brittle and thereby enables the use of a very thin zinc layer or plate 2, which is much cheaper and not so easily destructible, thereby reducing materially the cost of production and 30 lengthening the life of the zinc layer by several times that of a cell within the zinc layer or plate amalgamated with mercury only by reason of the fact that it permits the current to be employed in useful work alone 35 and not in local action. The life of the battery is also prolonged by its mechanical structure, in that it is impossible for the contained moisture to escape. In the ordinary zinc container battery the zinc plate is 40 the outside container and if a hole appears through faulty soldering, or is eaten through by reason of the corrosion, the battery dries out and dies whether being used or not, since the zinc itself forms the outer wall of 45 the battery. The outside container 1 in the device at issue thoroughly prevents evaporation regardless of the condition of the zinc layer or plate 2.

50 After the various elements have been assembled, as hereinbefore stated, a washer 8, preferably of card-board, is fitted snugly around the carbon pole 5 and snugly contacts with the inner wall of the container and on this washer 8 is placed a thin layer 55 of saw-dust or the like and upon this layer 9 is placed a second card-board washer 10 similar to the washer 8 and over the washer 10 is placed the sealing compound 11, which may be as now generally employed.

60 65 In the form of invention disclosed in Fig.

2, the various elements are the same except in lieu of the absorptive layer or plate 4 the carbon elements, including the pole and filler, are placed in a small cotton sack 12 and wrapped tightly with the cord 14 and 70 set in the container 1^a which has been previously prepared, as set forth with relation to the container 1, care being exercised to see that the bag does not contact with the zinc layer or plate 2^a. I find it of advantage 75 to have the same spaced therefrom about one-eighth of an inch. The bag is then surrounded by the gelatinous paste 15 and this gelatinous paste is permitted to remain in the container and serves as the exciting 80 paste. This form of construction makes a very long-lived battery, but the amperage is slightly lower, due to the increased internal resistance of the extra amount of paste. The paste 15 is of substantially the 85 same mixture as has been set forth relative to the saturation of the absorptive layer or plate 4 but is mixed as follows: The gelatin is soaked until soft in a small quantity of a solution of zinc chlorid dissolved in water 90 until it tests 32° Baume scale, to which sal ammoniac is added until the solution is saturated. The surplus solution is poured off and the gelatin warmed and the glycerin added. Then the sal ammoniac and zinc 95 chlorid are dissolved in as little water as possible and added to the glycerin and gelatin, the aluminum chlorid being added last. In this second form of my invention, the carbon moistening solution is prepared by 100 dissolving zinc chlorid in water until the gravity reaches 32° Baume. To this is added all the sal ammoniac it will dissolve, after which the mercury salt is added.

From the foregoing description, it is 105 thought to be obvious that an electrical battery constructed in accordance with my invention is of an extremely simple and comparatively inexpensive nature and is particularly well adapted for use by reason of 110 the convenience and facility with which it may be assembled, and it will also be obvious that my invention is susceptible of some change and modification without material departure from the principles and 115 spirit thereof and for this reason I do not wish to be understood as limiting myself to the precise arrangement and formation of the several parts herein shown in carrying out my invention in practice.

I claim:

1. An electrolyte comprising glycerin 1 oz., gelatin 8 oz., sal ammoniac 8 oz., aluminum chlorid 2 oz., and zinc chlorid 8 oz.

2. A battery of the character described including a container formed of pulp, and a metallic winding embedded therein.

3. A device of the character described comprising a container, a zinc plate therein, a layer of absorbent material in contact with 130

the inner face of the zinc layer saturated with a mixture including aluminum chlorid, and a filler including mercurial salts.

4. A battery of the character described including a container formed of pulp, and a reinforce for the container embedded within the pulp.

In testimony whereof I hereunto affix my signature in the presence of two witnesses.

WILLIAM HOPPIE.
